(57) **CLAIM**

The ornamental design for a water fountain, as shown and described.

DESCRIPTION

FIG. 1 is a top-front-left perspective view of a water fountain showing my new design;

FIG. 2 is a bottom-rear-right perspective view thereof;

FIG. 3 is a front elevational view thereof;

FIG. 4 is a rear elevational view thereof;

FIG. 5 is a left-side elevational view thereof;

FIG. 6 is an enlarged detailed view of area 6 of FIG. 5.

FIG. 7 is a right-side elevational view thereof;

FIG. 8 is a top plan view thereof; and,

FIG. 9 is a bottom plan view thereof.

The dashed lines showing two poles, a perch, a recording device, the main receptacle, and an electrical box mounted within the main receptacle, are included for the purpose of illustrating environmental structure and forms no part of the claimed design.

FIGS. 5 and 6 show dash-dot-dash broken lines that represent boundaries and indicator of the enlarged view. The broken lines form no part of the claimed design.
